UNITED STATES PATENT OFFICE.

CARROL H. OTT, OF JOHNSTOWN, PENNSYLVANIA.

NURSING-BOTTLE HOLDER.

1,220,266.

Specification of Letters Patent. Patented Mar. 27, 1917.

Application filed April 1, 1916. Serial No. 88,233.

To all whom it may concern:

Be it known that I, CARROL H. OTT, a citizen of the United States, residing at Johnstown, Cambria county, Pennsylvania, have 5 invented a new and useful Nursing-Bottle Holder, of which the following is a full, clear, and exact description, reference being had to the accompanying drawings, forming part of this specification, in which—
10 Figure 1 is a side view of a device embodying my invention, showing the parts in one position.

Fig. 2 is a sectional view showing one of the joints and the attached bottle holder, 15 different positions of the latter being shown in dotted lines.

Fig. 3 is a plan view of one of the joints, and

Fig. 4 is a plan view of the bottle holder.

20 My invention has relation to a device for holding nursing bottles; and is designed to provide a simple and convenient device which can be readily and quickly attached to and detached from any suitable adjacent support, and by means of which a nursing bottle may be securely held in any desired position. The device is provided with means whereby a universal adjustment of the bottle holder with respect to the clamping device is made possible, so that the bottle can be readily adjusted to various positions of the infant.

Referring to the accompanying drawings, in which I have shown a preferred embodiment of my invention which will now be described, the numeral 2 designates a suitable clamp. In the form of my invention shown, this clamp comprises a pair of jaws having a clamping screw 3, and adapted to embrace a support 4, which may be part of the frame of a bed or crib, a rail or arm of a chair, or other piece of furniture, or some part of a baby carriage, or any other convenient object. The form of the clamp may also be widely varied. The heel end of the clamp is provided with a socket 5 adapted to be rotatably engaged by a stud 6 on the clamp member 7. A clamping screw 8 is provided to secure the adjustment of the stud 6 in the socket 5. The joint member 7 is shown being in the form of a sleeve or barrel, within which is rotatably fitted a sleeve or barrel member 9 on the end of an extensible supporting rod 10. To permit differ-

ent angular adjustments of the rod 10, the joint member 7 has an arcuate slot 11 therein. The desired adjustment is obtained by means of a clamping screw 12, which engages the member 8 through the slot 11 and 60 clamps against the periphery of the member 7.

The supporting rod is formed in two sections, one of which is rotatably and telescopically engaged with the other, the desired adjustment being obtained by means of a clamping screw 13. The other member 10^a of the extension rod is secured at its outer end to a joint member 14 which is shown as being similar to the joint member 7, and within which is rotatably seated another joint member 15 which is similar to the member 9. The member 14 is circumferentially slotted throughout the greater portion of its periphery to receive a screw 16 75 which extends diametrically through the members 14 and 15. The screw is provided at one end with an adjusting nut 17, a spring 18 being preferably interposed between this nut and the member 14. Pivotally connected to an extension 19 of the screw 16 is a bottle holder 20 which may be in the form of a spring clamp, adapted to embrace a bottle in the manner shown. The connection between the holder 20 and the 85 screw extension 19 is preferably formed by means of a screw pivot 21, which also acts as a clamp to secure the holder in different angular positions with respect to the screw, as illustrated in Fig. 2. 90

The rotary connection between the stud 6 and the socket 5 permits the extension rod 10 and its attached parts to be swung into various positions with reference to the support 4. If the clamp 2 is engaged vertically with the support 4 as shown in Fig. 1, then the extension rod 10 may be swung through an entire circle in a horizontal plane. Similarly, if the clamp be engaged horizontally with the support the extension 100 rod can be swung through a complete circle in a vertical plane. The joint between the extension rod and the clamp formed by the members 7 and 9 also permits various angular adjustments of the extension rod in a 105 plane at right angles to that of its swinging movement. The rotary telescopic joint in the extension rod not only permits the distance between the two joints at the respective ends of such rod to be widely varied,

but it also permits these two joints to be adjusted in any desired plane with respect to each other. Thus, it will be obvious that instead of the two joints being in the same plane as shown in Fig. 1, the joint to which the bottle holder is attached may be turned into a plane at right angles to that of the other joint, or into various other angular relations thereto. The joint at the outer 10 end of the extension rod permits various angular adjustments of the screw 16; and the pivotal connection of the bottle holder with the extension of this screw gives further adjustments of the holder, some of 15 which are indicated in dotted lines in Fig. 2. It is therefore possible, in any case to bring the holder 20 into the most convenient and suitable relation to the child. The various adjustments can be quickly secured by 20 means of the clamping screws.

I do not desire to limit myself to the particular construction and arrangement of the parts which I have herein shown and described, as it is obvious that various changes 25 may be made within the spirit and scope of the appended claims. Thus, as above indicated, the form of the clamp 2 and of the bottle holder 20 may be widely changed; any suitable form of joints may be used at 30 the ends of the extension rod, and many other changes may be made.

I claim:

1. A device of the character described, comprising an extension rod having oscillating joints at each end thereof, a clamp 35 connected to one joint, each of said joints comprising a ring having a peripheral slot

therein and a ring rotatable therein, a screw passing through both of said ring members for securing the joint in position, and a 40 bottle holder connected to the joint opposite the clamp, substantially as described.

2. A device of the character described, comprising an extension rod, means for connecting one end of the rod to a supporting member, a joint on the other end of the rod having two ring members, one within the other, the outer ring member having a peripheral slot, a clamping screw extending through both ring members and arranged to 50 secure one ring in its adjusted position with relation to the other ring, and a bottle holder connected to the end of said screw, substantially as described.

3. A device of the character described, comprising a two-part extension rod the members of which are rotatably and telescopically engaged with each other, an oscillating joint at the outer end of one of the extension rod members, a clamp rotatably 60 connected to said joint, an oscillating joint at the outer end of the other extension rod member, a supporting device attached to the movable member of said joint, an adjusting device intermediate said clamp and joint and a bottle holder pivotally connected to the said supporting device, substantially as described.

In testimony whereof, I have hereunto set my hand.

CARROL H. OTT.
